UNITED STATES PATENT OFFICE

2,033,881

PILE FABRIC AND METHOD OF
MAKING SAME

Melville G. Curtis, Cynwyd, Pa., assignor to
Collins & Aikman Corporation, Philadelphia,
Pa., a corporation of Delaware

Application November 22, 1927, Serial No. 235,059

8 Claims. (Cl. 28—1)

My invention is an improved pile fabric having the loops of the pile enmeshed or interlocked in the backing fabric or base and united thereto by a solidified pliable composition which firmly attaches the pile and reinforces the base, and may render the base impervious to moisture, without detracting from the appearance or "feel" of the pile threads, which project beyond the surface of the coating composition. The pile may, if desired, be cut considerably shorter than is usually practicable. The adherent composition may be a quickly solidifiable cellulose solution, such as a viscose or pyroxylin compound, a rubber or rubber-and-glue solution, casein, or other agglutinant, and may be solidified by coagulation, vulcanization, heating or the like. Preferably the composition is substantially insoluble after solidification, and may be so colored as to give desired effects independently of or in conjunction with pile decoration resulting from printing, cutting, singeing, acid treatment or the like.

In the preferred practice of my invention, a double pile fabric is woven quite loosely, with 25 relatively few picks or weft threads over which the pile warps are looped. The fabrics resulting from cutting apart such double fabric would ordinarily be unsuited for any usual pile fabric use because of the shedding of the pile fibres 30 from the backing and the lack of firmness or body of the latter. These objections are overcome and desirable products produced, in accordance with my invention, by impregnating the backing with a suitable adherent composition as 35 above described which forms an insoluble adhesive preventing the dislodgement of the pile and reinforcing the backing fabrics. The pile may be split to separate the backing fabrics after the composition is solidified, or the splitting may 40 be done before the impregnation takes place. Instead of forming the pile from yarn or thread, it may be formed from filaments such as slightly 45 twisted slivers or rovings resulting in tufts which when cut expand or spring out to form a close pile surface.

The agglutinant composition may be applied to the base of the pile and to the backing in any suitable way which will leave the tips of the piles free, as, for instance, by impregnating the 50 backing by immersion in or contact with an agglutinant after the fabric has been woven, or by coating the weft threads with a rapidly solidifying viscous agglutinant.

The fabrics produced may be dyed or decorated by cutting, singeing or acid treatment in

any usual way and a back of suitable shade, texture and form provided by using an agglutinant of suitable color and composition.

My improved product is particularly adapted for upholstery and floor coverings and a leading object of my invention is the production of a pile fabric with the pile firmly secured to a backing having a minimum number of picks or weft threads, which can be loosely, rapidly and economically woven and impregnated with the adherent composition to strengthen the backing and unite the pile base thereto while leaving the pile tips free. A further object of my invention is to produce a pile fabric from which the pile can be cut to form a very short nap without causing shedding.

A further object of my invention is to render practicable the utilization of rovings or slightly twisted slivers for the formation of pile. Further advantages and characteristics of my invention will appear from the following description of illustrative embodiments of my invention and the accompanying diagrammatic drawing in illustration thereof.

In the accompanying drawing, Fig. 1 illustrates diagrammatically a double pile fabric embodying my invention and which is being split to form pile fabric such as illustrated in Fig. 2; Fig. 3 illustrates diagrammatically a fabric embodying my improvements and having uncut loops woven therein, as in terry cloth or some types of carpet; and Fig. 4 illustrates diagrammatically a split pile fabric embodying my improvements and having the piles formed of rovings or loosely twisted slivers.

As illustrated diagrammatically in Figs. 1 and 2, the double pile fabric 1 has its backings woven respectively from the warps 1, 2 and wefts 3 and from warps 4, 5 and wefts 6 and connected by pile warps 7 and 8 looped over the weft threads 3 and 6. The tips of the bights of the pile loops form small elevations, knobs or knots, which for lack of a better term may be called nodules, which are sufficiently numerous and close together to give a roughened or granulated effect to the back. Of course, the weaving may be done in any manner desired to form a pattern or the like by floating any of the warps at desired intervals. In order to decrease the number of weft threads and increase the output, the weft threads 50 may be beaten up quite loosely so that the wefts are relatively widely spaced and the pile warps are but loosely bound by the engagement of the threads so that such fabrics lacking an adhesive composition are unfit for dyeing or finishing.

The pile warps are, however, firmly fixed to the backing fabrics by an adherent composition applied to the weft threads during weaving or to the backing fabrics after weaving, and which permeates the backings so that when the composition solidifies it forms a flexible tenacious layer or bed 9 securely embedding the looped pile threads without obliterating the nodules formed by the tips of the bights thereof, uniting the pile to the base fabrics and permitting the fabrics to be cut apart by a cutter 10, handled and dyed without shedding fibres. As shown in Fig. 2, the resultant products have their pile extending above the backing and from the bed of impregnating material to form a pile which may be cut very short and is securely held against dislodgement. The protuberance of the tips of the pile bights from the general level of the surface of the bed 9, and preferably through such bed, gives the product a textile feel and appearance on the back, since the roughness caused by the protuberances or nodules is not obliterated or substantially obscured by the substance permeating the backing, and the textile characteristics of the product are impaired but slightly, if at all, since the bed 9 lies primarily in the interstices of the ground yarns and its bottom surface lies above the tips of the pile bights, when the fabric is considered as lying with its cut pile face upward.

As illustrated in Fig. 3, a single pile fabric is formed by weaving pile loops 11 around the weft threads 12 of a loosely woven backing and are secured in place by a solidifiable adherent substance 13 securely attaching the bottom of the pile loop to the backing fabric such substance forming a bed lying principally within the thickness of the fabric as measured from its cut face to the tips of the pile bights. The outer loops 40 may be left uncut, or may be cut by a pile wire, or by a machine in a usual manner to form a pile surface.

Fig. 4 illustrates diagrammatically a split pile fabric having the pile formed of tufted filaments 14 produced by utilizing slightly twisted slivers or rovings as pile warps. The tufts are looped over the spaced wefts 15 of a loosely woven backing and are secured in place by a solidifiable adherent layer or bed 16, which may be applied while sufficiently fluid to impregnate the backing and leave the tips of the pile bights projecting to form a rough or nodulated back.

Having described my invention, I claim:

1. A pile fabric having a nodulated back and comprising a loosely woven backing, pile threads woven through said backing and forming a pile face on one side of said backing and forming bights on the other side of said backing producing a nodulated surface, and a bed of normally insoluble pliable adherent substance in said backing and binding together said backing and pile, the tips of said pile bights protruding from said bed and the protuberance of such tips giving a textile feel to the back of the fabric which is not obliterated by said substance.

2. A pile fabric having ground yarns forming a loosely woven backing including wefts, pile warps forming V-pile on said wefts, and a bed of normally insoluble pliable adherent substance permeating said backing and binding together said backing and pile, said bed lying within the thickness of the fabric as measured from its pile face to the tips of the bights of the pile V's, and such

tips of the pile bights projecting from said bed and forming a nodulated surface giving to the back of the fabric a textile feel which is not obliterated by said substance.

3. A pile fabric having a nodulated back and comprising a loosely woven backing, pile warps woven through said backing and having cut ends expanded to form a close pile surface, said pile warps forming V's having bights projecting from said backing opposite to said pile surface, and a bed of pliable adherent substance binding together said backing and pile, said bed lying within the thickness of the fabric and having its lower surface broken by the tips of the pile bights and disposed above such tips when the fabric is considered as lying with its cut pile face upward, the protuberance of said tips giving a textile appearance to the back of the fabric which is not obliterated by said substance.

4. In the manufacture of pile fabrics, the steps which consist in simultaneously fabricating a backing and pile loops having bights forming a nodulated surface on said backing, then permeating said backing with an adherent substance, and solidifying said substance into a pliable bed in said backing which does not obliterate the tips of said pile bights, such tips projecting from said bed to form a nodulated surface.

5. In the manufacture of pile fabric, the steps which consist in loosely weaving a backing and simultaneously forming pile loops therein having bights forming with said backing a nodulated surface, permeating said backing with an adherent substance, solidifying said substance into a pliable bed in said backing and from which bed the nodules comprised in said surface project, and dyeing and finishing the pile after the solidification of said bed.

6. A pile fabric having ground yarns forming a loosely woven backing containing wefts, warp pile threads looped through said backing over each weft and forming bights on one side and projecting pile ends on the opposite side of said backing, said backing being too loosely woven to alone firmly hold said warp pile threads for any usual pile fabric use, and a flexible adherent material permeating said backing and securing said warp pile threads to said backing while leaving said bights and pile projecting beyond the surface formed by the permeated yarns of said backing.

7. A V-weave warp pile fabric having a backing formed of interlaced ground warps and wefts, V-pile tufts looped over each of said wefts and forming bights on one side and projecting cut ends on the opposite side of said backing, said backing being too loosely woven to alone firmly hold said warp pile loops for any usual pile fabric use, and a normally insoluble, flexible, adherent material permeating said ground yarns and securing said warp pile threads to said backing, said bights forming a perceptibly nodulous surface which is not obliterated by said adherent material.

8. A pile fabric having a loosely woven backing, pile tufts formed of slightly twisted fibres which when cut expand or spring out to form a close pile surface, said backing being too loosely woven to alone firmly hold said pile tufts, and a normally insoluble, flexible, adherent material permeating said backing and tufts and securing said tufts to said backing, said tufts forming projecting bights on the back of the finished fabric.

MELVILLE G. CURTIS.
